Primary Examiner — Sandra Snapp*Assistant Examiner* — Russell Carnell Smith, Jr.(74) *Attorney, Agent, or Firm* — Sughrue Mion, PLLC(57) **CLAIM**

The ornamental design for an audio speaker, as shown and described.

DESCRIPTION

FIG. 1 is a front perspective view of the audio speaker showing the new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict portions of the audio speaker and form no part of the claimed design.

1 Claim, 7 Drawing Sheets(56)
